ADOLPH F. CHRISTMAS, OF EASTON, PENNSYLVANIA, ASSIGNOR TO INGERSOLL-RAND COMPANY, OF JERSEY CITY, NEW JERSEY, A CORPORATION OF NEW JERSEY.

GOVERNING FUEL-PUMP.

1,352,050

Specification of Letters Patent. Patented Sept. 7, 1920.

Application filed September 28, 1918. Serial No. 256,129.

To all whom it may concern:

Be it known that I, ADOLPH F. CHRISTMAS, a citizen of the United States, residing at Easton, in the county of Northampton and State of Pennsylvania, have invented a certain new and useful Improvement in Governing Fuel-Pumps, of which the following is a specification.

This invention relates to a fuel pump and 10 especially to a pump adapted to force fuel oil from a source of supply into the combustion chamber of an internal combustion engine. More particularly, the invention relates to a pump of the above type provided with means for controlling or varying 15 the amount of fuel pumped into the combustion chamber to maintain a constant speed of the engine under varying conditions of load.

20 The objects of the present invention are to provide a fuel pump for internal combustion engines which will accurately control and vary the amount of fuel required on each stroke, to provide a pump that will always start pumping the fuel at exactly the 25 desired point in the stroke of the engine and will continue the pumping until just a sufficient amount of oil has been admitted into the combustion chamber after which the 30 remaining amount of oil displaced by the pump plunger will be by-passed back into the fuel supply. Another object of the invention is to provide a fuel pump for internal combustion engines which will be very 35 sensitive to variations in the position of the governor and that will be simple, rugged and not easily put out of order.

With the above and other objects in view 40 my invention consists in the features of construction and operation set forth in the following specification and illustrated in the accompanying drawings, forming a part hereof, in which

45 Figure 1 shows a top plan view of the pump; and

Fig. 2, a vertical section taken longitudinally of the pump.

50 Referring more particularly to the figures of the drawing, 1 refers to the body portion of the injecting pump provided with a plunger or piston 2 operating within a cylinder 3 provided within the body portion 1. The cylinder at one end is provided with valve cages 4 in which are placed balls 5 acting as discharge valves for the fuel liquid and

above the cylinder 3 the valve cages 4 connect with a fuel discharge pipe 6 leading to the point of injection which may be in the form of an injection nozzle placed within the combustion chamber of the combustion 60 engine. Below the cylinder 3 the body portion 1 is provided with a plurality of valve seats 7, against which rest the balls 8 serving as suction valves for the pump, below which is the fuel supply pipe 7a.

65 The plunger 2 is operated within the cylinder 3 by means of a cam 9 rigidly fastened to the shaft 10 to which is attached the crank arm 11. At the free end of crank arm 11 a connecting rod 12 is pivotally attached, 70 the opposite end of which is in attachment with an eccentric or cam mounted on the main shaft of the engine (not shown) by means of which it is given a movement in synchronism with the rotation of the main 75 shaft and thus the plunger is forced forwardly into the cylinder 3 once for each revolution of the crank shaft of the engine. The plunger 2 is guided in its movements within the cylinder 3 by means of a head 13 80 slidably fitted within a portion of a bracket member 14 securely fastened to the body portion 1 by any well known means.

85 The above described mechanism provides a pump which will always pump the same amount of fuel with each stroke of the plunger 2. Also, the arrangement of the cam 9 is such that a portion of its movement does not affect the movement of the plunger 2, the plunger remaining stationary until a 90 point is reached in the path of movement of the cam as shown in Fig. 2 at which point the velocity of the cam is at a maximum and at which point the pump begins its forward stroke. The displacement of the plunger 2 95 within the cylinder 3 at each stroke is equal to or greater than the maximum amount of fuel required for one power stroke of the engine. In order to permit the amount of fuel pumped to be varied an extra valve 15 100 independent of the suction and discharge valves of the pumps 5 and 8 respectively is provided conveniently located within a portion of or extension to the cylinder 3. This valve 15 may also be of the ball type 105 having its seat provided in the body portion 1, as shown at 16. A spring 17 normally presses against the ball 15 and holds it securely against its seat so that all the fuel pumped by the plunger 2 must pass 110

out of the pump past the discharge valves 5 and into the supply pipe 6 as long as the valve 15 remains closed.

A rod 18 extends from the valve seat 16 to a point adjacent the cam 9, and its end away from the valve seat 16 extends slightly beyond the bracket member 14. Suspended above the bracket member 14 is a lever 19 pivoted at 20 and moved upwardly and downwardly by means of a lever 21 connected to a movable member of a governor (not shown) so that with variations in the speed of the engine the position of the lever 19 is varied. Depending from the lever 19 is a wedge shaped finger 22, so placed that its lower end is located directly in front of the rod 18. The cam 9 is provided with an extension 23 in which a plunger 24 is adapted to be retained and held in its forward position by means of a spring 25 and held from being forced out of its cavity by means of nuts 26. Movement of the cam 9 with its projection 23 causes the plunger 24 to impinge upon the wedge 22 which in turn forces the rod 18 to the right and unseats the valve 15. It is obvious that with the wedge 22 in different positions the valve 15 will be unseated at different points in the movement of cam 9 and consequently in different points in the stroke of the plunger 24. The function for the plunger 24 is merely to permit the continued movement of the cam 9 after the valve 15 has been unseated. The spring 25 is provided of sufficient resistance to unseat the valve 15 without causing movement of the plunger 24 within its cylinder. As soon as the valve 15 is unseated fuel contained within the cylinder 3 is by-passed through valve 15 into a pipe 40 27 through which it is passed back into the source of supply and no further fuel is discharged through valves 5 into the combustion chamber. For starting the engine a lever 28 is provided shown in dotted lines 45 in Fig. 2 fitted to turn about the shaft 10 and operate a cam 29 to move the plunger 2 forwardly to deliver a charge of fuel to the combustion chamber.

From the above it will be seen that a fuel pump has been provided which will pump a variable amount of fuel dependent upon the location of the movable members of the governor and consequently sensitive to the speeds of the engine.

It is to be understood that the present showing and description disclose only one specific embodiment of the present invention and that other forms and modifications are included within the spirit and scope of the invention, as expressed in the appended claims.

What I claim is:

1. In a fuel pump for internal combustion engines, a plunger adapted to reciprocate within a cylinder to force motive fluid from a source of supply into a combustion chamber, means for actuating said plunger, a by-pass valve normally held closed, a device operatively connected to the plunger actuating means for opening the by-pass valve, and means controlled by a governor for controlling the opening of said by-pass valve at variable points toward the end of the stroke of the plunger to vary the amount of fuel admitted to the combustion chamber.

2. In a fuel pump for internal combustion engines, a plunger adapted to reciprocate within a cylinder to force motive fluid from a source of supply into a combustion chamber, means for actuating the said plunger, a spring closed valve and means operatively connected to said plunger actuating means and controlled by a governor to open said valve to by-pass a portion of the fuel and vary the amount of fuel supplied to the combustion chamber.

3. In a fuel pump for internal combustion engines, a plunger operating within a cylinder to force fuel oil into an internal combustion engine; a valve normally held closed and located within a portion of said cylinder, means for operating said plunger and means under the control of a governor to open said valve at variable points toward the end of the stroke of the plunger without stopping the engine.

4. In a fuel pump for internal combustion engines, a plunger operating within a cylinder to force fuel oil into said engine, a by-pass valve normally held closed during the early portion of the stroke of the plunger and means under the control of a governor to open said valve near the end of the stroke of the plunger to by-pass a portion of the fuel pumped without stopping the engine.

In testimony whereof, I have hereunto set my hand:

ADOLPH F. CHRISTMAS.
